GELATIN PREPARATION

Walter M. Urbain, Chicago, Ill., assignor to Industrial Patents Corporation, Chicago, Ill., a corporation of Delaware

Application May 2, 1941, Serial No. 391,461

16 Claims. (Cl. 250—52)

This invention relates to the preparation of dry protein material in a substantial sterile condition, and more particularly it is directed to a method and apparatus for preparing gelatin suitable for edible purposes substantially free from bacteria and molds.

Gelatin is commonly prepared by a method involving hot aqueous extraction from a suitable source material such as hides or bones which have had albuminous and mucinous matter removed therefrom, concentration of the aqueous gelatin extract in evaporators, spreading of the concentrated gelatin solution as a thin film upon a moving belt, chilling the concentrated gelatin on the belt until it sets up into a jelly, removing the wet gelatin film from the moving belt, and drying it on a suitable support. As is clearly evident, the product, especially when employed in food preparations, should be substantially free of bacteria. Every precaution is therefore employed by the manufacturers to prevent contamination of the gelatin product with bacteria or mold. However, it has been found that even when operating under very closely controlled, sanitary conditions throughout the process, the final product will often be infected with bacteria. This unfortunate result seems to occur more frequently in the summer than in the winter. A detailed study has shown that the chilled gelatin jelly is generally free from bacteria but that the dried film is usually contaminated.

It has now been found that the source of contamination is the presence of bacteria on the supports for the chilled gelatin film during the drying period. Even though these supporting frames or screens are kept in a clean condition it has been found that they are the origin of the contamination. If the frames are free of bacteria there seems to be no substantial development of bacteria in the gelatin film during the hot drying period. The drying step is particularly conducive to bacteria development because of the increased temperature for substantial periods of time, but it has been found that in normal operation unless the gelatin is infected by the frames or supports during this period there is no substantial increase in bacteria count. However, the screens which are re-used for supporting fresh sheets to be dried are found to develop bacteria rather readily.

In spite of the fact that attempts are made to keep the frames clean, they retain small particles of gelatin which, because of the nature of the frame or screen surfaces, are not always removed in the cleaning process. The gelatin

particles, lumps or films serve as foci of infection for subsequent sheets of jelly. Because of the longer periods that these contaminated particles of gelatin are in the warm air drying chamber they develop an exceptionally high bacteria count. These infected areas in contact with the gelatin sheet undergoing drying infect the sheet. The drying period then amounts to an incubation which develops the infection, resulting in a high count gelatin. In the summer time the usual high humidity necessarily increases the drying time and consequently increases the incubation period.

Wet methods of cleaning and sterilizing the supporting screens are not desirable because the wood framework of the screens on repeated wetting and drying will harden and sometimes twist out of shape. Furthermore, the process is long, and the labor costs are very high. Dry methods of disinfecting the screens likewise cause drying out and breaking of wood frames, and as in the wet methods take considerable time. Chemical methods have the added disadvantage of the possibility of contamination of the edible gelatin to be dried while supported on the frames. Because of the infection throughout the gelatin particles or films contaminating the screen, simple surface-sterilizing methods cannot be used alone.

It has now been found possible to prepare gelatin substantially free from bacteria conveniently by the standard procedures. The present process comprises, in general, the irradiation of the supporting frames with ultra-violet radiation of sufficient intensity to materially disinfect the frames including the gelatin contaminant thereon just prior to placing on said frame the gelatin jelly sheet to be dried in the air drying chamber. Until this invention, it has been generally accepted that ultra-violet radiation could only be used for air and surface sterilization or for sterilization of thin films of water or the few other substances which similarly readily transmit ultra-violet light. On the contrary, it has now been determined that it is possible to sterilize substantial thicknesses of gelatin particles infected with bacteria not only at the surface but substantially throughout it in a very short time of exposure and at a relatively low cost. Considering the relatively great thickness of the gelatin films or particles which adhere to the screens or frames, it is surprising that the substantial sterilization of the frames and adherent gelatin particles can be effected by the present process since the absorption of ultra-violet rays is very great by even thin layers of material and increases rapidly with in-

creased thickness. The unusual results obtained could not be predicted on the basis of previous knowledge of ultra-violet sterilization and the treatment of gelatin with such rays. For example, in Comptes rendus, CLI, 219 (1910) it is stated that the ultra-violet light from a 3.5 ampere mercury vapor lamp at a distance of 15 centimeters had only a superficial action on gelatin gel and that it did not proceed deeper after a certain minimum duration of exposure because of the opacity of gelatin to rays of short wave length. In addition, Steenbock, United States Patent No. 1,871,135, discloses that with the ordinary mercury vapor lamp irradiation of various materials, among which is gelatin, antirachitic activation is effected but not sterilization. However, substantially complete sterilization has been effected in a fraction of a minute by the present method. This is startling since sterilization of other organic compounds by earlier ultra-violet procedures either was effected in very thin films, or was accomplished with thicker particles, such as lumpy sugar which could not be sterilized in fifty minutes by direct radiation, only after two minutes of treatment by shaking to expose fresh surfaces. (J. Ind. and Eng. Chem., vol. 31, p. 1168, 1939.)

It has been discovered that it is essential that the effective ultra-violet radiation be of sufficient intensity that the rays penetrating through substantial layers of material are still of sufficient intensity, e. g., about 25 microwatts per square millimeter, to cause a rapid abiotic action. This is obtained by a high intensity source of ultra-violet radiation in excess of 25 microwatts per square millimeter (at the surface) by an amount governed by the thickness and the coefficient of absorption of the gelatin or other protein contaminant on the screen. For example, with average conditions of operation the surface intensity of 50 to 100 microwatts per square millimeter of active radiation has been found satisfactory although less may prove operative depending on the type and intensity of contamination and time of treatment. The period of treatment preferably should be sufficiently long to yield substantial sterilization, usually to obtain a total active irradiation of about 5,000 microwatt seconds per square millimeter, but this varies depending on the type and intensity of contamination, the intensity of the lamp, and other factors. Prior opinions of ultra-violet sterilization did not consider gelatin to have a relatively high transmittancy for radiation of wave lengths shorter than 2,800 Angstroms. Therefore, believing that sterilization could not be effected, earlier workers either would not have attempted to sterilize the gelatin by this means or would have used the usual low intensity ultra-violet sources to accomplish the result of questionable value; namely, simple surface sterilization.

The ability of high intensity radiation to penetrate gelatin is demonstrated by the following experiment. A number of gelatin drying screens employed in conjunction with a K. & L. gelatin casting machine were dipped in a 10% aqueous gelatin solution which had a high bacteria count. The gelatin adhering to the screens was permitted to dry. To the coated screens was then applied a gelatin jelly prepared from the high count solution, after which the screens were again dried. These pieces of jelly were about one-fourth inch thick and one inch in diameter before drying, and shrank to a thickness of about one-sixteenth inch after drying. Particles this size are about as large as any encountered in ordinary factory op-

erations. Some of the inoculated gelatin coated screens were irradiated with a three hundred and sixty watt Uviarc lamp at a distance of about eight inches for different irradiation periods.

- 5 Following the irradiation a sterile 10% aqueous gelatin jelly was laid on the screens and after incubation at room temperature for 24 hours this gelatin was dried in a wind tunnel and stripped off the screens aseptically. The bacterial count 10 of this gelatin from the different frames was observed and the results are given in the following table.

TABLE I

Irradiation period	Bacteria per gram of gelatin
Seconds	
0	420,000
15	660
60	10

It is apparent from these results that the dried gelatin from the highly contaminated screens which had been irradiated by the high intensity ultra-violet rays had a much lower and more satisfactory bacterial count. The conclusion is therefore drawn that the radiation from the high intensity Uviarc lamp was of sufficient intensity that in the short time periods listed sufficient penetration was obtained to substantially sterilize the contaminated gelatin present in relatively thick pieces. The 360 watt fused quartz mercury arc lamp or Uviarc lamp employed in the above experiment has an arc length of about six inches maximum, a rating of 54 watts per arc inch, and develops 284 microwatts of ultra-violet energy per square millimeter at 10 centimeters. It has an over-all length of 10 $\frac{1}{16}$ inches and a diameter of $\frac{3}{4}$ inch maximum. The radiation characteristics of the lamp are as follows:

TABLE II

Regions (wave length, Å.)	Approximate microwatts per sq. cm. at 1 meter distance from lamp
25,000-14,000 far infra red	47
14,000-7,000 near infra red	95
7,000-4,000 visible	299
4,000-3,100 near ultra-violet	237
3,100-2,800 middle ultra-violet	91
2,800-1,850 far ultra-violet	193

This data indicates that the lamp is a high intensity lamp and is not to be confused with the low intensity germicidal or Sterilamps commonly employed for surface sterilization.

60 Although good results are obtained by using the lamps alone, it has been found advantageous to employ reflectors for the lamps not only in back of the lamps but on the other side of the screens in order to throw back as much of the ultra-violet light as possible, thus increasing the efficiencies of the lamps about 50%, and also protecting the workers in the surrounding area.

65 The metal employed affects the efficiency of reflection, the order of preference being roughly: stainless steel, stellite, nickel plate, polished aluminum, polished tin and Duralumin.

In commercial operation the location for the installation of the ultra-violet lamps depends on the following considerations:

1. The lamps must effectively irradiate all the surfaces of the screens.
2. Sufficient exposure must be obtained by the correct combination of the number of lamps, intensity of radiation, and time of exposure.
3. The interval of time between irradiation and use of the screens should be as short as possible.
4. The lamp should be mounted so as not to interfere with the continuous operation of the chilling and drying apparatus, e. g., a K. & L. machine.
5. Protection must be provided for the operators against the actinic rays and glare, and ozone generated by the lamp.

The commercial installation represented in Figures I and II of the accompanying drawing represents a satisfactory compliance with the above listed requirements in a K. & L. apparatus. Figure I is a side elevation of a modified K. & L. machine and Figure II is a view of the same machine in perspective.

A concentrated gelatin solution is poured on the endless flat rubber belt 1 which then passes through a chilling chamber 2. The belt 1 has raised edges to hold the fluid solution to the required height. The gelatin solution in passing through the chilling chamber 2 is jelled. At the end of the chamber 2 where the chilling belt 1 passes over the large drum 3 the gelatin jelly sheet is stripped from the belt 1 by scraper 5. The gelatin jelly sheet 4 is then carried by the endless take-off belt 6 on a series of pulleys to the rotary cutter 7 which cuts the jelly sheet into two longitudinal strips. The gelatin strips are then cut transversely by rotary cutter 8 into sheets about five feet long. The high intensity lamps 9 are mounted below the endless belt 6. Mounting them in this position requires the raising of the take-off belt 6 from its usual position to make room for the lamps which are in the enclosing hood 12. In the large scale apparatus for commercial production employing 1,200 watt lamps, it is usually desirable to place two or three pairs of lamps side by side so that the radiation covers about three feet of the length and the entire width of the frames or screens 10, moving on the endless open belt or chain 11 at a distance of about eight inches under the lamps 9. This develops at least 300 microwatts per square millimeter of active ultra-violet radiation. Four such lamps are generally sufficient to provide adequate exposure when the K. & L. chilling belt 1 is operated at maximum speed, usually about ten feet per minute. A polished stainless steel reflection plate 13 is placed under the screen to reflect a substantial quantity of the ultra-violet light and to increase the efficiency of the lamps. The screens 10, substantially sterilized by the treatment at this point, move but a short distance before the cut chilled gelatin strips 4 are placed thereon by the take-off belt 6; hence no appreciable time intervenes between the sterilization and use of the screens. The loaded screens are removed from the endless belt as it passes over the gear 14 and are placed on movable supporting racks (not shown) which are removed to a drying chamber through which passes a stream of warm, relatively dry air. Protection for the workers against actinic rays and glare is provided by the hood 12 and suitable shielding. Ozone generated by the lamps is removed by drawing air by means of an exhaust fan (not shown) out of the room past the lamps 9 at a rate of 2,000 cubic feet a minute through the

twelve inch duct 15. This ventilation also serves to cool the lamps 9, adding to their effective life. The following table shows the effectiveness of the radiation of the screens in commercial production of gelatin satisfactory from a bacterial standpoint.

TABLE III

	No. of lamps	Conveyor belt speed, ft. per min.	Irradiation period per unit area, sec.	Bacteria per gm.

0	10	0	780,000	

In obtaining the above data artificial drying conditions approximating high humidity or delayed drying operation were made by holding the gelatin jelly in a warm, humid place for twenty-four hours prior to drying. This was done to simulate summer operations which are often so unsatisfactory that plant operations have to be stopped to avoid production of gelatin of high bacteria count.

The 1,200 watt Uviarc lamp used in the above described commercial operation is a fused quartz mercury arc lamp having the following characteristics:

TABLE IV

It develops about 1,420 microwatts per square millimeter of active ultra-violet radiation at ten centimeters. The above characteristics including power consumption and ultra-violet radiation output demonstrate that this is a high intensity source of ultra-violet. This lamp may be effectively employed at distances of two feet from the irradiated surface.

A satisfactory lamp should have sufficient radiation of low wavelength below the limit of about 3,600 Angstroms. The shortest rays have the most lethal action and it is preferred to employ lamps emanating a substantial radiation

having wavelengths less than 2,800 Angstroms. The 1,200 watt lamps not only has 17% of its radiation in the highly active range, but its high overall power produces an exceptionally high quantity of total short wave radiation. In other words, there is a great quantity of high intensity radiation that is well above the minimum threshold intensity of ultra-violet radiation to effect lethal action, usually of the order of 25 microwatts per square millimeter. Above this value the lethal action depends on the time and to a great extent on the intensity of ultra-violet radiation, which two values fix the total quantity of radiation. Although about 5,000 microwatt seconds per square millimeter radiation is extremely effective with the above-discussed lamp under ordinary conditions of operation, increased intensity of active ultra-violet radiation may reduce this volume, and vice versa. The intensity of the 1,200 watt lamp is so exceptionally high that not only short times of exposure are possible, but even in those short times more than simple surface sterilization is obtained.

The present operation is so effective that, even though periodic washing of the screens is given for assuring proper operation, the screens are sterilized without the removal of the substantial quantities of accumulated gelatin on the screens usually accomplished by such washings.

The ordinary germicidal or sterilamps have an operating wattage of only about ten to fifteen watts, or about one to one and one-half watts per arc inch, and a highly active ultra-violet intensity of only fifteen to twenty microwatts per square millimeter at ten centimeters. The 1,200 watt lamp develops about seventy to ninety-five times the ultra-violet light produced by the usually employed lamp. To accomplish the same result with the small commercial low-intensity lamps as with the large high-intensity lamp is not only impractical, but probably impossible because of the problem of getting sufficient lamps in a position to irradiate simultaneously the same surface with about the same energy consumption.

The above procedure for treating the screens is substantially different than the direct irradiation of dry gelatin, gelatin solutions or gelatin jelly, since it effects the production of substantially sterile gelatin without physical modification or deterioration which results from treating gelatin directly with ultra-violet radiation. Treatment of gelatin in various forms with certain ultra-violet radiation will affect the viscosity, solubility, swelling, whipping properties, taste, odor and various other properties, depending on the form during treatment as well as the duration and intensity of treatment.

As many widely different modifications and embodiments of the invention hereinbefore set forth may be made without departing from the spirit and scope thereof, only such limitations should be imposed as are indicated in the following claims.

I claim:

1. In the process of drying films of gelatin jelly, the steps which comprise irradiating the drying frame with high intensity ultra-violet radiation of an intensity greater than twenty-five microwatts per square millimeter for a time sufficient to substantially sterilize the frames and any gelatin adhering thereto and prior to any substantial recontamination applying a gelatin film for drying on the sterilized frame so that a substantially sterile film of gelatin jelly dried thereon is obtained.

2. In the process of drying films of gelatin jelly, the steps which comprise irradiating the drying support with ultra-violet radiation of an intensity greater than twenty-five microwatts per square millimeter for a period of time that the total irradiation is five thousand microwatt seconds per square millimeter and sufficient to substantially sterilize any gelatin adhering thereto and prior to any substantial recontamination applying gelatin to the sterilized support for drying.
3. In the process of drying films of gelatin jelly, the step which comprises irradiating the drying support immediately prior to placing the gelatine to be dried thereon with the rays from at least one twelve hundred watt, high intensity, ultra-violet, fused quartz, mercury arc lamp at a distance of not more than two feet from the frame for a period sufficient to sterilize the support and any gelatin adhering thereto.
4. In the process of drying films of gelatin jelly, the steps which comprise irradiating the drying support with ultra-violet radiation of an intensity of not less than fifty microwatts per square millimeter for a sufficient period to substantially sterilize the support and any gelatin adhering thereto and promptly thereafter applying to the sterilized support the gelatin for drying.
5. In the process of drying films of gelatin jelly, the step which comprises irradiating the drying support immediately prior to placing the gelatin to be dried thereon with ultra-violet radiation of an intensity of not less than fifty microwatts per square millimeter for a sufficient period that the total irradiation is five thousand microwatt seconds per square millimeter.
6. In the process of drying films of gelatin jelly, the steps which comprise irradiating the drying support with ultra-violet radiation of an intensity of not less than one hundred microwatts per square millimeter for a sufficient period to substantially sterilize the support and any gelatin adhering thereto and prior to any substantial recontamination applying gelatin to the sterilized support for drying.
7. In the process of drying films of gelatin jelly, the steps which comprise irradiating the drying support with ultra-violet radiation of an intensity of not less than three hundred microwatts per square millimeter for a sufficient period to substantially sterilize the support and any gelatin adhering thereto and promptly thereafter applying to the sterilized support the gelatin for drying.
8. In the process of drying films of gelatin jelly, the step which comprises irradiating the drying support with ultra-violet radiation of an intensity of not less than three hundred microwatts per square millimeter for a period of time that the total irradiation is five thousand microwatt seconds per square millimeter, said irradiation being made just prior to the placing of the gelatin jelly film thereon.
9. A process for the manufacture of dried gelatin material of low bacterial content wherein gelatinous material is dried on a drying support normally tending to retain impurities which contaminate the gelatin dried thereon, which comprises treating the support with ultra-violet radiation of sufficient high intensity to substantially sterilize the surface of the support and any particles of gelatin material retained thereon and immediately thereafter placing the gelatinous material on said support for drying.
10. A process for the manufacture of edible

gelatin of low bacterial count wherein the gelatin jelly is dried in films on screens normally tending to retain on the surface thereof impurities, including particles of gelatin which contain a high bacterial count, and to contaminate the gelatin films dried thereon, which comprises subjecting the screens to ultra-violet radiation of sufficient high intensity to substantially sterilize the surface thereof and any particles of gelatin adhering thereto and immediately drying the gelatin films on the sterilized screens.

11. In an apparatus for treating gelatin, the combination of a source of ultra-violet radiation, a reflector, means for conveying gelatin screens between the source of radiation and the reflector, and means for depositing films of gelatin on the screens immediately after passing between said source of radiation and said reflector.

12. In an apparatus for treating gelatin, the combination of a conveyor means for gelatin screens, a second conveyor means superimposed on said first conveyor means for depositing sheets of a gelatin on said screens, and one or more high intensity ultra-violet lamps for irradiating and sterilizing said screens immediately prior to depositing the gelatin sheets thereon.

13. A process for the manufacture of dried gelatin material of low bacterial content which comprises treating the drying support with ultra

violet radiation of sufficient high intensity and for a period of time sufficient to substantially sterilize the surface of the support and any gelatin adhering thereto and prior to any substantiation recontamination applying the gelatin to said support for drying.

14. A process for the manufacture of dried gelatin material of low bacterial content which comprises treating the drying support with ultra violet radiation of sufficient high intensity and for a period of time sufficient to substantially sterilize the surface of the support and any gelatin adhering thereto and prior to any substantial recontamination applying the gelatin to said support for drying.

15. In an apparatus for manufacturing gelatin, the combination of a source of ultra violet radiation, means for subjecting for a predetermined time a support for a gelatin film to rays from said source of radiation and means for depositing said gelatin film on said support promptly after the irradiation thereof.

16. In an apparatus for manufacturing gelatin, the combination of a source of ultra violet radiation, means for exposing for a predetermined time a support for a gelatin film in radiation relation with said ultra violet and means for depositing said gelatin film on said support immediately after irradiation thereof.

WALTER M. URBAIN.
